UNITED STATES PATENT OFFICE.

MALCOLM WRIGHT AND HENRY BECKER, OF BALTIMORE, MARYLAND.

SAFETY LOCK.

Application filed March 28, 1921. Serial No. 456,446.

To all whom it may concern:

Be it known that we, MALCOLM WRIGHT and HENRY BECKER, citizens of the United States, residing at Baltimore, in the State of Maryland, have invented certain new and useful Improvements in Safety Locks; and we do hereby declare the following to be a full, clear, and exact description of the invention, such as will enable others skilled in the art to which it appertains to make and use the same.

This invention relates to improved safety locks for preventing accidental operation of a valve used in steam turbine practice known as a vacuum breaker. Valves of this type are designed to be operated by manual and independent mechanically controlled means and it not infrequently happens that accidental operation of the valve is caused by a person brushing against the manual-valve-operating means. It is the object of this invention to provide a safety device which will prevent accidental operation of the valve, the locking means being of such character that it must be positively released before the vacuum breaker can be manually operated. The locking device is so constructed as to permit the vacuum breaker to be operated by the mechanically controlled means which, as already indicated, is independent of the manual operating means.

The various novel features of the invention will appear from the detailed description taken in connection with the accompanying drawings forming part of this specification, and in which:

Figure 1 is a side elevation of the vacuum breaker showing the improved locking means attached thereto, and

Fig. 2 is a vertical section taken through the mechanism shown in Fig. 1.

In the drawings, 1 indicates an upright frame which is adapted to be secured at its base to any suitable support and 2 is a shelf projecting laterally adjacent the bottom of the frame for supporting a valve casing or body 3 having a valve seat 4 therein. 5 is a valve adapted to make an air-tight connection with the valve seat 4 and having a valve stem 6 which passes through a sleeve or collar 7 in the head 8 of said casing, that portion of the casing or body below the head being of open work construction and having standards or pillars 9 for supporting the head 8. Surrounding the valve stem 6 between the collar 7 and valve 5 is a spring

10 which serves to keep the valve to its seat. The casing 3 below the valve seat is provided with an opening 11 which is in communication with a pipe 12 which leads to a vacuum chamber forming part of the turbine mechanism not shown. When the valve 5 is raised from its seat, the pipe 12 is open to the atmosphere, and consequently the vacuum is destroyed.

The manual means for elevating the valve 5 from its seat comprises a hand lever 13 pivoted to a standard 14 projecting from the frame 1, the lever having a bifurcated ball end 13' for straddling a rod 15 which at its lower end is connected to the upper end of the valve stem 6 as by being threaded thereon as shown at 16. The upper end of the rod 15 is provided with a suitable head or as shown at 15'. It will be understood that upward pressure beneath the head 15' by the lever 13 will elevate the valve 5 from its seat.

The frame 1 is provided with a laterally extending head 17 through which the rod 15 projects. Affixed within the head 17 is a sleeve 18 having an inner shoulder forming a seat for a spring 19 which surrounds a sleeve 20 which is telescoped over the rod 15 and slidably mounted within the said sleeve 18. The upper end of the sleeve 20 is provided with a suitable head as a cap 21 against which the upper end of the spring 19 reacts. The spring 19 is of the expansion type and tends to move the sleeve 20 upwardly with respect to the sleeve 18. When the sleeve 20 moves upwardly the rod 15 will be carried with it, upward pressure being exerted below the head 15' of the rod, through the bifurcated end 13' of the lever 13 as will be readily understood.

Pivotedly mounted on the fixed sleeve 18 as at 22, is a latch or trip lever 23 which is adapted to be connected as at 24 to certain turbine governing means not shown. The bottom of the sleeve 20 is provided with a shoulder 25 against which the latch 23 abuts. When the latch is in the position shown in Fig. 1, upward movement of the sleeve 20 is prevented. When the latch 23 is operated by the governing means in connection with the turbine, the sleeve will be moved upwardly by the spring 19, consequently the valve 5 will be lifted from its seat to open the pipe 12 to the atmosphere.

In order to prevent the valve 5 from being accidentally lifted from its seat by the

hand lever 13 there is provided a key 26 which passes through a slot 27 in the rod 15 where the latter projects through the lower end of the sleeve 20. This key is connected 5 by a pin and slot connection 28 to a hand lever 29 which is pivoted as at 30 to a bracket 31 affixed to one of the standards 9 of the casing or body 3. A spring 32 exerts pressure to maintain the key 26 within the 10 slot 27.

It will now be apparent that when the latch 23 is in engagement with the shoulder 25 of the sleeve 20 as shown in Fig. 1 and the key 26 is engaged with the rod 15 15 and in abutting relation with the lower end of the sleeve 20, as shown in Fig. 2, that the valve 5 cannot be lifted from its seat by the lever 13. Before the valve can be so lifted the key 26 must be disengaged from 20 the rod 15. This arrangement, therefore, effectually prevents operation of the valve 5 through accidental manipulation of the hand lever 13. However, upward movement 25 of the valve 5 is permitted when the latch 23 is disengaged from the shoulder 25 of the sleeve 20 by reason of there being a pin and slot connection 28 between the key 26 and lever 29, it being understood that the slot in the lever 29 is of sufficient length to 30 allow proper range of movement of the key 26 to allow the valve 5 to be raised from the seat.

The improved locking device is simple and can be readily attached to existing vacuum 35 breakers with but very little change being made in the operating parts thereof.

We claim:

1. In combination, a frame, a valve stem 40 slidably mounted in the frame, a plurality of means for axially moving the valve stem,

and means for locking the valve stem against movement by one of said means, but not against movement by the other of said means.

2. In combination, a frame, a valve stem 45 slidably mounted in the frame, a spring-pressed sleeve telescoping said stem, means releasably locking said sleeve against displacement in one direction, means locking said valve stem against displacement in the 50 said direction when the sleeve is locked as said, means for operating said valve stem independently of the sleeve when the valve-stem locking means is released, and means permitting said sleeve when released to 55 operate the valve stem when the latter is locked against independent movement.

3. In combination, a frame, a valve stem, slidably mounted in the frame, a pair of means for operating said stem, means for 60 locking the stem against movement by one of said means but not by the other, and means for releasing said means to permit operation of the stem by the said one means independently of the other.

4. In combination, a frame, a valve stem, means on the frame for operating said stem, a key normally carried by said stem, an abutment against which the key engages to prevent upward movement of the valve stem 70 by said operating means, means rendering said abutment movable at times for operating said stem, and means for withdrawing the key from the stem to permit movement of the stem independently of the abutment. 75

In testimony whereof we affix our signatures.

MALCOM WRIGHT.
HENRY BECKER.
